US0D1014199S

(12) **United States Design Patent** (10) **Patent No.:** **US D1,014,199 S**
Zhou (45) **Date of Patent:** **** Feb. 13, 2024**

(54) **STRAINER**

(71) Applicant: **Guangdong Transcontinental Technology Co., Ltd.**, Guangzhou (CN)

(72) Inventor: **Hong Zhou**, Shenzhen (CN)

(**) Term: **15 Years**

(21) Appl. No.: **29/829,768**

(22) Filed: **Mar. 8, 2022**

(51) LOC (14) Cl. **07-04**

(52) U.S. Cl.

USPC **D7/667**; D7/368

(58) **Field of Classification Search**

Assistant Examiner — Ji Sun Yoon

(57) **CLAIM**

The ornamental design for a strainer, as shown and described.

DESCRIPTION

FIG. 1 is a front perspective view of a strainer, showing my new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a bottom view thereof; and,

FIG. 8 is a top view thereof.

The broken lines in the drawings illustrate the portions of the strainer, which form no part of the claimed design.

1 Claim, 8 Drawing Sheets
